WILLIAM H. REYNOLDS, OF TOLEDO, OHIO, ASSIGNOR TO THE MEILINK MANUFACTURING COMPANY, OF TOLEDO, OHIO, A CORPORATION OF OHIO.

LOCKING DEVICE FOR SAFES, &c.

961,088.

Specification of Letters Patent. Patented June 7, 1910.

Application filed April 12, 1909. Serial No. 489,349.

To all whom it may concern:

Be it known that I, WILLIAM H. REYNOLDS, a citizen of the United States, residing at Toledo, Lucas county, Ohio, have invented new and useful Locking Devices for Safes, &c., of which the following is a specification.

This invention relates to holding devices, and more particularly to forms of bolt throw mechanisms and the means for operating such mechanisms for locks.

This invention has utility when embodied in a lock for safes.

Referring to the drawings: Figure 1 is a rear elevation, with parts broken away of an embodiment of the invention in a lock for a safe; and Fig. 2 is a side elevation, partially broken away, of the structure shown in Fig. 1.

20 Abutting the rim or stop 1 is the flange 2 overlapping the mounting plate 3. The flange 2 is integral with the outer or finishing plate 4 which has the annular rib 5. Centrally disposed as to these door plates 25 3, 4, is the spindle 6, having loosely mounted thereon the disks or tumblers 7, 8, 9. The tumbler 9 may be locked at various adjustments to the spindle 6 by means of a screw carried by the arm 10, which arm 10 is 30 fixed to the spindle 6. This screw carried by the arm 10 may engage with some one of the holes 11 in the tumbler 9. Protruding from the disk or tumbler 9 on the side toward the door is the pin 12, which may 35 have any selected location. In the line of travel of the pin 12 of disk 9, is the pin 13 extending through intermediate disk 8, the portion of which pin 13 not on the side engaged by pin 12, is in the line of travel of 40 pin 14 projecting from the disk 7, which pin 14 has a selected location in said disk in accordance with the combination chosen. The changes in position which may be made 45 of pins 12, 13, 14, permits of a wide range in the number of possible combinations. The disks 7, 8, have radially disposed notches 15, while disk 9 has the notch 16 into which the pawl or dog 17 may engage when the disks are so arranged as to bring the 50 notches 15 and 16 in position adjacent this pawl or dog 17. The spiral spring 18 surrounding the pivot mounting 19 of the pawl 17 serves to keep this dog against the peripheries of the tumblers. The pivot 19 55 for the pawl 17 is carried by the pawl car-

rier or cam plate 20 loosely mounted concentric with the spindle 6. This bolt actuating or bolt engaging cam plate 20 mounted on the pivot or spindle 6 has a plurality of cam slots 21 therein, engaged by the 60 screw pins mounted in the forked ends of the radially reciprocable locking devices or holding bolts 22, guided by bolt engaging guides or brackets 23 carried by the mounting plate 3 of the door. Concentric with 65 the circular door and shielding the locking mechanism is the housing 24 having lugs 25, through which screws 26 extend to firmly mount the housing on the door, by engaging in holes 27 in the plate 3. Openings 70 28 are provided in the housing 24, for the bolts 22. The bolts 22 on being thrown radially outward by the cam slots 21, with the door in position against one side of the stop 1, co-act with the opposite side of the 75 stop, serving as an effectual holding device.

The showing in Fig. 1, is with the pawl 17 dropped, so that a slight further turn of the spindle 6 will withdraw the thrown bolts. This turning of the spindle 6 to withdraw 80 the bolts would move the pawl 17 to the left in Fig. 1. A movement of the spindle 6 to the right, would cause the bevel of notch 16 to actuate the pawl 17 outward, while rod bracket 23, the one of the bolt engaging devices adjacent the pawl provides a stop to limit the outward throw of the pawl. The pawl in this outward position rides on the peripheries of the tumblers and permits the 85 combination to be thrown off by further rotation of the spindle 6 to the right in order that the pins 12, 13, 14, may disarrange the 90 grouping of the tumblers. As usual in combination locks, the spindle is twirled one direction more times than there are tumblers, and then alternately in opposite directions in accordance with the combination to line up the notches of the tumblers for the 95 pawl 17.

The combination herein disclosed of a lock, illustrated as of the permutation type, with a bolt throw holding scheme, is compact, substantial, and has the further advantage of requiring but one hole through the door through which the lock may be operated as well as the bolts thrown. The arrangement of the bolts and their mounting is such that they may be thrown simultaneously in a plurality of directions by rotation of the permutation lock spindle. The 100 105 110

pawl which serves to connect the lock spindle to the bolt throw plate, travels concentrically with the spindle to perform this function. In mounting the movable pawl on the door, it is not necessary to always have the pawl above, or in any other fixed relation as to the spindle, so there is no clue to guide a safe-breaker as to the point which door should be drilled to locate the pawl. The spindle 6, rotatable relatively to the door, may operate the permutation lock and then automatically operatively connect through the tumblers and pawl with the cam plate to throw or withdraw the holding bolts.

15 What is claimed and it is desired to secure by Letters Patent is:

1. The combination with a round door of a permutation lock comprising a pawl, a spindle rotatably mounted in said door, radial locking bolts for said door, operatively connecting means for actuating said bolts through said pawl including a mounting member for the pawl concentric with the spindle, and bolt engaging guides holding 25 said door against rotation relatively to the bolts.

2. The combination with a round door, of radial locking bolts for the door, a spindle rotatably mounted in the door, bolt engaging guides holding said door against rotation relatively to the bolts, and means operable to connect the spindle to the bolts including a bolt actuating plate, a pawl, and a mounting member for the pawl movable 35 concentrically with the spindle.

3. The combination with a door, of locking bolts for the door, a spindle rotatably mounted in said door, and means operable to connect the spindle to the bolts including 40 a cam plate engaging the bolts, tumblers mounted on the spindle and actuatable therefrom, and a pawl mounted on said plate and connecting the tumblers to the plate, whereby the spindle may be connected to and disconnected from the bolts.

4. The combination with a door, locking bolts for the door, and bolt engaging guides holding the door against rotation relatively to the bolts, of a spindle rotatably mounted 50 in said door and means for connecting and disconnecting the spindle to the bolts, said means comprising a plate for actuating the bolts, a pawl mounted on said plate, and tumblers connected to the spindle and operable therefrom to move the pawl.

5. The combination with a door, of lock-

ing bolts for the door, a spindle rotatably mounted in said door, and means for connecting the spindle to operate the bolts, said means comprising a cam plate rotatable to 60 throw the bolts, tumblers mounted to be gathered up and set by the spindle, and a pawl for connecting the tumblers and plate mounted on one thereof to engage the other and to transmit motion from the spindle to 65 the bolts for their simultaneous movement.

6. The combination with a spindle, a door, locking bolts for the door, and bolt engaging guides holding said door against rotation relatively to the bolts, of means for 70 throwing said bolts by rotation of said spindle relatively to the door, said means comprising a pawl, a slotted mounting member for the pawl, said member being provided with a pivot bearing to permit oscillation, 75 there being a connection between the member and bolts through the slotted portion of the member, and tumblers actuatable from the spindle to connect the spindle to the pawl.

7. The combination with a round door of radially movable locking bolts for the door, a spindle rotatable relatively to said door, permutation tumbler mechanism operable from said spindle, and connecting means 85 between the mechanism and bolts whereby rotation of the spindle may withdraw the bolts, said means including a rotatable plate mounted on the spindle and connected to the bolts.

8. The combination with a rotatable spindle of radially movable bolts, of means for operating the bolts from the spindle, said means including a pawl carrier and tumbler mounted on the spindle, and a pawl 95 movable to connect the carrier and tumbler, said carrier connected to the bolts, and said tumbler connected to the spindle.

9. The combination with a door of a plurality of bolts, a spindle rotatably mounted 100 in said door, and means for actuating the bolts from the spindle, said means including a cam plate engaging the bolts and permutation lock mechanism operable to connect the spindle to the cam plate.

In testimony whereof I hereunto set my hand in the presence of two witnesses.

WM. H. REYNOLDS.
